LOCKING DEVICE

Jeremiah W. Albin, Babylon, N. Y.

Application March 5, 1937; Serial No. 129,172

6 Claims. (Cl. 24—221)

The present invention relates to a locking and particularly relates to a locking device which may be generally applied to attaching cowls, covers, hoods, and so forth, to mounting structures.

Although not specifically restricted thereto, the present invention may be particularly described in connection with its application to a hood or cover locking devices upon automobiles or airplanes in which a cover of metallic or other similar material is to be rigidly attached or locked to a mounting plate or latch structure.

It is among the objects of the present invention to provide a simple locking construction of the character described which will be of inexpensive construction, may be readily operated to make a rigid connection which will not permit of rattling and which may be utilized for long periods of time without damage and without breakage.

Other objects will be obvious or will be apparent during the course of the following specification.

In accomplishing the above objects, according to one embodiment of the present invention, it has been found most suitable to provide a key member having a resilient wing structure.

This key is held or fixedly pivoted upon one of the plates or elements to be locked together, while the other element is provided with a key slot to receive said resilient wing and with a resilient locking means therefor.

Preferably, said second member is provided with a resilient plate member or other spring means to firmly hold said resilient wing in position when the same has been inserted through the key slot and turned.

In the drawing is shown one preferred embodiment of the present invention, to which, however, the invention is by no means limited. This embodiment is shown merely by way of illustration and not by way of limitation.

The above and other objects will appear more clearly from the following detailed description when taken in connection with the accompanying drawing which will illustrate a preferred embodiment of the inventive idea.

Referring to the drawing:

Figure 1 is a front view of the locking device of the present invention partly showing the elements to which the locking device is attached.

Figure 2 is a rear view of the combination of Figure 1.

Figure 3 is a transverse sectional view upon the line 3—3 of Figure 2 across the junction.

Figure 4 is a transverse sectional view upon the

line 4—4 of Figure 1 along the line of the junction.

Figure 5 is a perspective view showing fragments of the two elements to be locked together carrying the key and resilient lock just before the key is inserted into position.

Referring to Figures 1 to 4, the plate 10 and the plate 11 may take any desired form and may be extensions or portions of the hood, casing or cover of an automobile or some other construction.

The front plate 10 carries the key structure 12, while the rear plate 11 carries the latch structure 13.

The key structure consists of a base 15 having a fin 16 serving as a finger grip portion, said key having a shank 17 which extends through an opening 18; said key being held in position by the ring 19 attached to said shank on the other side of said opening.

Beyond the ring 19 the shank has a continuation or stem 20 which is provided with openings 21 to receive the ends 22 of the bow shaped resilient member 23, the bow also extending through an opening 24 in said stem 20.

The bow element or wing shaped element 23 is preferably made of a resilient wire, which is firmly held in said stem 20 by the openings 21 and 24.

The resilient latch 13 consists of a bowed plate 25 which is riveted at 26 to the rear plate 11, the opposite sides of outside bowed edges 32 being provided with recesses 27 into which the bottom elements 28 of the bows are designed to snap in the manner best indicated in Figures 2 and 3.

In operation, the locking device may be locked into the position shown in Figures 1 to 4 by turning the key 12 ninety degrees from its position shown and then inserting the spring bow 23 into the key slot 30, the stem 20 fitting into the enlarged central portion 31 of said key slot 30 (see also Figure 5).

At this time the bow 23 will be positioned parallelly of the bow element 13 and upon being turned ninety degrees in either direction, the lower elements 28 of the bow 23 will ride over the edges 32 of the plate 25 and finally snap into the recesses 27 where a firm and rigid lock will be obtained.

It will be noted that the inside plate 11 is offset at 34 so that its offset portion 35 may rest in the back of the plate 10 and permit the outside portions of two plates 10 and 11 to be flush with each other, this being best shown in Figure 3.

It is thus apparent that the present application has provided a simple, inexpensive and read-

ily manipulated locking device of general application to automobile constructions or to other uses and which is of particular value in places where a durable, inexpensive and strong locking construction is desired.

It will be noted that the key element 12 may be turned in either direction to lock the device and that the resiliency of the plate 28 together with the snap of the element 28 into the recess 27 will give a firm connection which will not tend to loosen with rattling or shaking of the device to which the lock is applied.

It is apparent that the specific illustrations shown above have been given by way of illustration and not by way of limitation and that the structures above described are subject to wide variation and modification without departing from the scope or intent of the invention, all of which variations and modifications are to be included within the scope of the present invention.

What is claimed is:

1. A fastener of two parts, said fastener comprising a key device adapted to be rotatably mounted on one of said parts, and a plate element having at least one upturned free side edge,

said key device having at least one lateral projection element and said upturned side edge being shaped to engage said projection element, at least one of said elements being resilient, the plate element being provided with means whereby it is mounted on said other part.

2. The fastener of claim 1, said plate having opposite upturned free side edges and said key device having opposite lateral projection elements adapted to engage both said side edges.

3. The fastener of claim 1, said plate element and said other part being provided with cooperating central openings to receive said key device.

4. The fastener of claim 1, said plate element being resilient.

5. The fastener of claim 1, said means consisting of rivets positioned adjacent one side and adjacent each end of said upturned side edge.

6. The fastener of claim 1, said key device having opposite lateral projection elements and said plate element being slotted parallelly to said upturned side edge to receive said projection elements.
